UNITED STATES PATENT OFFICE.

WILLIAM ZEEDYK, OF PATERSON, NEW JERSEY, ASSIGNOR TO BENJAMIN EASTWOOD COMPANY, OF PATERSON, NEW JERSEY, A CORPORATION OF NEW JERSEY.

STOP-MOTION FOR LOOMS.

1,360,487.

Specification of Letters Patent. Patented Nov. 30, 1920.

Application filed December 13, 1918. Serial No. 266,571.

To all whom it may concern:

Be it known that I, WILLIAM ZEEDYK, a citizen of the United States, residing at Paterson, in the county of Passaic and State 5 of New Jersey, have invented certain new and useful Improvements in Stop-Motions for Looms, of which the following is a specification.

This invention relates to weft stop motion mechanisms for looms and it consists, first, in a novel construction of the means for detecting the absence of weft or filling and thereupon transmitting the motion of the batten to movable means on the fixed part of the 10 loom which shifts the knock-off shaft to position for stopping the loom, and, second, in a novel construction whereby the mechanism can be used, as herein shown and described, as a "center" stop motion (operative to detect absence of filling on each pick instead 15 of every other pick, as in the case of the so-called "side" stop motion mechanisms) and particularly so that when so used said movable means shall be disposed in inoperative 20 position with reference to the first means herein alluded to for the first pick of the loom following absence of filling and consequent stopping of the loom, *i.e.*, until the shuttle on its second shot following the 25 starting up can have laid the filling in operative relation to the detecting means, under its weft fork.

Figure 1 in the drawings is a side elevation of a loom embracing my stop motion 30 mechanism;

Fig. 2 is a front elevation of the essential parts of what is shown by Fig. 1;

Fig. 3 is a plan view of a fragment of the batten, the weft fork and its bracket;

Fig. 4 shows the improved stop motion 40 mechanism in side elevation, the batten appearing in section and the breast-beam-including part of the loom frame in side elevation, and the power controlling lever appearing partly in section; in this figure the batten is assumed to be moving forward and filling being absent the weft fork and dagger are shown by solid lines in operative position to cause actuation of the slide and consequent 45 stopping of the loom;

Fig. 5 is a plan view of what is shown in Fig. 4, both the brake lever and power controlling lever being here shown, partly in section;

Fig. 6 is a view substantially similar to

Fig. 4 excepting that the batten appears full back and the weft fork elevated to permit passage of the shuttle, and except that the slide appears elevated so that on the ensuing forward movement of the batten said slide 60 will not receive the impact of the dagger, this view showing the said levers moved to the starting position and the batten about to advance in the first cycle of the loom following such movement of the levers;

Figs. 7, 8 and 9 are views showing the slide in side elevation and the lever which it controls and certain parts which control the slide in section, Figs. 7 and 9 showing the slide in the positions it occupies before and 70 after actuation by the dagger and Fig. 9 showing the slide in the position it occupies so as to clear the dagger on the first pick following a starting-up;

Fig. 10 is an underneath plan of the slide; 75 and

Fig. 11 is a sectional view on the lines 11-11 of Fig. 5.

The batten structure *a* is fulcrumed in the loom frame *b* at *c* in the usual way and is 80 connected with the crank shaft *d* by the pitman *e*. From the drive shaft *f* the power is transmitted to the crank shaft through a clutch (not shown) on shaft *d*, and this clutch is controlled by the aforementioned 85 power-controlling lever, *g*, fixed on the knock-off shaft *h* and operatively connected with the clutch in any way, as by the link *i*. There is also a brake pulley *j* fast on the shaft *d* and around this brake pulley and 90 fixed at one end to the frame is a brake-band *k*, the other end of which is connected to the rear arm of a two-armed lever *l* which is fulcrumed at *m*, said rear arm of the lever being subject to the pull of a spring *n* which 95 normally tends to exert braking tension on the brake-band, the forward arm of the lever having a roll *o* against which a roll *p* on the lower end of the knock-off or brake-lever *q* (fulcrumed on knock-off shaft *h*) bears 100 when the brake lever occupies the position shown in Figs. 1, 4 and 6 to hold the forward end of the lever *l* depressed so that the brake band is relaxed and the pulley *j* and shaft *d* are free to turn. To start the loom the 105

lever *g* is pulled forward (to the position in Fig. 1) and by a lug *r* on said lever the brake lever is thus pushed forward, releasing the brake-band *k*; to stop the loom the brake lever *g* is pushed back which releases the 110

lever *l*, so that the brake-band again becomes active on the pulley *j*, and through the lug *r* throws back the power controlling lever *g* to disengage the clutch. The foregoing parts are all well known.

5 A plate *s* is bolted to the breast-beam *A* at one end thereof and on a stud *t* adjustable in a slot *u* in the plate is fulcrumed a lever *v*, one arm of which is in the path of movement of the brake lever *g*, its other arm being engaged in a notch *w* in the side of the slide *x* which may move forward and back in a suitable groove *y* in the top of the plate and has at the end thereof adjoining the front of the loom a pair of lateral ears *z* engaged in undercut opposite grooves *2* in the plate. There is a keeper-arm *3* secured to the lever *v* and overhanging the slide (Fig. 11), allowing it to rise 10 to a limited extent at its forward end on its ears *z* as a fulcrum. The forward end of the slide depends and is formed with a notch *4*. Bolted to an overhanging portion of the plate *s* is a depending bracket 15 *5* having a horizontally slotted arm *6*. There is journaled horizontally in the plate *s* a light rock shaft *7* to which is secured by the set screw *8* a two-armed stop *9* which affords means to receive an impact for 20 rocking the shaft in one direction and also serves to limit the rocking motion of the shaft to approximately 90°, by said stop impinging as to one arm thereof against the top of plate *s* when the shaft rotates in one 25 direction and as to the other arm thereof against a depending lug *10* on the plate *s* when said shaft rotates in the other direction. The rock-shaft has a bent portion 30 forming a crank which is arranged at an acute angle with respect to that arm of the stop which is to the left in Fig. 4, and connecting this crank with a hook *12* on the plate *s* is a spring *13*; the construction is such that on turning the shaft in either 35 direction past the position where the crank occupies the dead center relation to the point at which the spring is attached the spring will turn the shaft to the limit afforded by one or the other of the arms of the 40 stop *9*. The rock shaft also has a crank *14* which is in the path of knock-off movement of the knock-off lever *q*. On the rock shaft and under the slide is fixed a cam *15* whose high point projects upwardly, 45 thus elevating the slide, when the stop *9* is in the vertical position (Fig. 6), abutting the lug *10*.

The weft fork consists of a collar *16* equipped with feeler arms *17* which play up 50 and down in the usual recess *18* in the batten *B*, the collar being fixed on a light shaft *19* which is journaled in brackets *20* and *21* attached to the batten, the latter housing the collar *16*. This bracket *21* includes an upwardly extending arm *22* pene-

trated by a threaded stud *23* which forms a hammer to impinge against that arm of the stop *9* which is uppermost in Fig. 6, said stud being held in the arm *22* for adjustment relatively toward and from said stop 70 by the nuts *24*. A light spring *25* coiled about the shaft *19* and connected to bracket *21* at one end and to a collar *26* on said shaft at its other end tends to hold the weft fork depressed. The free end of shaft *19* is bent off to form a crank *27* and this crank supports the dagger *28* which is pivoted at *29* between a pair of vertical cheeks *30* of bracket *21* and when the weft-fork is fully depressed is held by the spring *25* bearing with a stop face *31* thereon, longitudinally alined with the free end of the dagger, against a stop face *32* on the bracket and rearward of the dagger, so that when the dagger acts to move slide *x* and stop 80 the loom the shock is received by the bracket *21* and not by the pivot of the dagger.

On a stud *33* adjustable in the slot *6* of a bracket *5* is pivoted a wire-link *34* having 90 an elongated loop *35* receiving a pin *36* on the side of the dagger.

The slide *x* has on the under side a pair of inclined cam surfaces *37* to engage the plate *s* at the points *38* (Fig. 5), when the slide is forced back by the dagger, as hereinafter explained.

Operation: So long as the loom operates without failure of filling the dagger on each beating-up movement of the batten 100 will obviously assume the dotted line position in Fig. 4 and so clear the slide *x*. If the filling fails, the dagger will assume the full-line position in Fig. 4 and when the batten moves to beat-up the dagger will 105 engage in the notch *4* of the slide and consequently cause lever *v* to impart knock-off movement of lever *q*, and consequently lever *g*. Comparatively little movement of the lever *v* is required to cause roll *p* of the knock-off lever to clear roll *o*, and when this movement is accomplished it is unnecessary to advance the slide farther; hence, when the said movement is about complete 110 the inclines *37* on the under side of the slide ride up on the plate *s* so that the slide clears the dagger (see Fig. 8). When the loom is started again, the resetting of the knock-off lever will obviously through 115 lever *v* move the slide forward again, though not in position to be engageable by the dagger, as in Fig. 4, but in the position to be missed by the dagger, as in Fig. 9, as will appear. It will be understood that the 120 link *34* causes depression of the dagger and consequent elevation of the weft fork each time the batten recedes, in order to allow the shuttle to pass under the weft fork.

When failure of weft occurs, the loom 125

stops while the batten is performing the forward movement which causes knocking-off movement of the lever *g*. Thereupon the weaver usually releases the brake, by pulling forward on brake lever *g*, and pushes the batten back so that he can perform certain manipulations of the shuttle and filling necessary to reestablishing the weft in the weaving process. On now starting the loom 10 again by pulling forward lever *g* the first forward movement of the dagger with the batten would obviously result in another stopping of the loom (since there is no filling yet present under the weft-fork to hold 15 the dagger depressed clear of the slide) were it not for the cam 15, which, when the lever *g* was moved to the knock-off position and by striking crank 14 rocked the shaft 7 to the position shown in Fig. 6, became turned 20 to hold the slide out of the path of the dagger, so that the latter will miss it (Fig. 9). The resetting of the slide in position to be engageable by the dagger (Fig. 7) is effected, immediately following the dagger thus 25 missing the slide, by contact of the hammer 23 with the upper arm of stop 9, resulting in rocking the shaft 7 to the (normal) position shown in Fig. 4, so that by the time the dagger makes its next or second forward movement 30 the shuttle will have passed again across the batten to lay the filling under the weft-fork and so hold the dagger depressed to clear the slide, unless of course there has occurred another failure of filling.

35 It is not broadly new to provide for rendering the mechanism inactive to stop the loom on the first beating-up movement following stopping; but this has usually been accomplished by a shield which on 40 stopping is automatically locked in position to fend the dagger off and prevent its actuating the knock-off mechanism for the first beating-up movement after starting, to be tripped by the batten to clear the dagger 45 for the second beating-up movement. It is obvious that my construction avoids the impact (as of the dagger with such a shield) characterizing the known mechanism referred to.

50 Having thus fully described my invention, what I claim and desire to secure by Letters Patent is:

1. In combination, with the supporting structure and moving batten structure of a loom, knock-off means including an actuated member on said supporting structure, and weft-controlled means to actuate said member including a dagger projecting toward said member from the batten structure and 55 movable up and down in the latter and normally impelled downward, a weft-fork device pivotally arranged in the batten structure and having an eccentric portion in wiping contact with an under face of the dagger 60 longitudinally of the latter, said device be-

ing normally turned on its pivot in the direction to elevate the dagger and thus normally holding the latter elevated, and means to move the weft controlled means in the opposite direction on backward movement of 70 the batten structure.

2. In combination, with the supporting structure and the moving batten structure of a loom, a movable knock-off member carried by said supporting structure, a batten-structure-moved weft-controlled train of parts for actuating said member on a forward movement of the batten structure and including a coengaging dagger and slide, the slide being shiftable pivotally on an axis remote from the dagger to clear itself therefrom, and means on movement of said train by the batten structure to shift said slide on its axis clear of the same thereby to dis-establish said train. 75

3. In combination, with the supporting structure and the moving batten structure of a loom, a weft-controlled dagger on the batten structure movable therein into and out of a given path of movement therewith, a movable knock-off mechanism including a dagger-actuated slide adapted to be moved by the dagger in said path relatively from the batten structure and resettable toward the batten structure and to a position out 95 of said path, movable means, actuated by the knock-off mechanism on movement of said slide by the dagger, to establish said slide in said position on the resetting of said slide toward the batten incident to 100 again starting the loom, and means, upon the dagger missing said slide on its first forward movement with the batten after such starting, to move the first means and thereby establish said slide back in said path. 105

4. In combination, with the supporting structure and the moving batten structure of a loom, a weft-controlled dagger on the batten structure movable therein into and out of a given path of movement therewith, 110 a movable knock-off mechanism including a dagger-actuated slide adapted to be moved by the dagger in said path relatively from the batten structure and resettable toward the batten structure and to a position out 115 of said path, rocking means, adapted to be rocked in one direction by the knock-off mechanism on movement of said slide by the dagger, to establish said slide in said position on the resetting of said slide toward 120 the batten incident to again starting the loom, and means, upon the dagger missing said slide on its first forward movement with the batten after such starting, to rock the first means in the other direction and 125 thereby establish said slide back in said path.

In testimony whereof I affix my signature.

WILLIAM ZEEDYK.
